Patented Nov. 4, 1919.

UNITED STATES PATENT OFFICE.

HARRY E. JAMES, OF ST. PAUL, MINNESOTA.

STORE-FRONT CONSTRUCTION.

1,320,864.

Specification of Letters Patent.

Patented Nov. 4, 1919.

Application filed March 19, 1918. Serial No. 223,285.

To all whom it may concern:

Be it known that I, HARRY E. JAMES, a citizen of the United States, residing at St. Paul, in the county of Ramsey and State of Minnesota, have invented a new and useful Improvement in Store-Front Construction, of which the following is a specification.

This invention relates to store front construction, the primary object being to provide more substantial construction in which a free and more efficient circulation of air is permitted over the inner surface of the glass, in which provision is made for more effectively draining water produced by condensation on the inner side of the window glass or from the washing of the glass, and in which the construction can be more easily cleaned than in prior devices. Among further objects are to provide a construction, in which the plate of glass can more easily and more effectively be secured in place and by the use of which the sash is rendered substantially weather proof. Still further objects are greater simplicity and less expensive construction and the provision of means whereby the air duct or ducts may be closed or opened wide when desired. In prior devices these objects are attained to a less degree than by my invention, but they are very difficult to clean. This objection is entirely overcome by my invention.

To these ends my invention comprises the features of construction and combination of parts hereinafter more particularly described and claimed.

In the accompanying drawing forming part of this specification, Figure 1 is a front elevation of a detail of a store front constructed in accordance with my invention, and Fig. 2 is a cross section taken on the line X—X of Fig. 1.

In the drawing let A indicate a detail of the sill or base of a window sash, case or store front, B the floor of such window or case and C the usual glass plate. D indicates a gutter element at the inner side of said plate preferably made of a body strip 2 of wood or other suitable material having a thin metal sheathing 3 over its exterior extending over the top and opposite sides. This gutter element is formed with a concave upper surface 4, which produces a gutter and the plate C rests with the lower portion of its inner surface against one side of the gutter element, being pressed tightly so that any condensation or water running

down the inner face of the plate flows into the gutter. The gutter element is mounted securely upon the floor element B and is provided with any suitable number of combined air and ventilating ducts E, which lead downwardly at spaced intervals or at any suitable point from the gutter through the body strip 2 and inclined forwardly and downwardly through the floor B and sill A, its lower end terminating and opening to the outer atmosphere through the front or outer wall of the sill. The lower edge of the glass plate C rests upon a cushion strip 5 made of wood or other suitable material. A thin sheathing 6 made of metal or other suitable material is placed over the front surface and top of the floor B to protect the latter from the elements, said sheathing being bent at right angles or otherwise shaped to cover the front 7 and exposed portion of the top 8, the upper inner edge 10 of said sheathing being bent upwardly at right angles to engage back of the lower front side 9 of the sheathing 3 on the gutter element and interlocking therewith. The upper portion of the sheathing 6 extends below the cushion strip 5 and the upturned flange 10 prevents any water which may drip down or flow under the plate 7 flowing or creeping back over the floor B and below the gutter strip. The lower outer extremity of the sheathing 6 extends downwardly below the floor and then upwardly and inwardly, so as to form a drip edge 11 to prevent water from flowing back under the floor B. The plate C is secured in place on the cushioning strip 5 and against the gutter element by means of the molding strip F, which is of skeleton form being made out of thin sheet metal and secured tightly upon the floor and against the lower outer edge of the plate and the outer face of the cushioning strip 5 by means of screws 12 or other suitable means passing downwardly through the molding element and into the floor. Each of the combined drain and ventilating ducts is produced by a casting of metal or a piece of other suitable material, which diverges downwardly and outwardly so as to produce a free passage for any liquid flowing down from the gutter to the exterior. This duct is broad as compared with its thickness so as to provide greater area for the egress of liquid from the inner surface of the plate and its upper end is closely joined at 13 to the sheathing

4 over the gutter element. The lower outer end 14 of said duct is flush with the front surface of the sill and is provided with a closure 15 in the form of a plate, which is 5 secured by a screw 16 or other suitable means threaded into the structure of the duct E to close the duct when desired. Normally when it is desired to circulate air up 10 over the inner surface of the plate C, the closure element 15 is removed, but during extremely cold weather or when it is desired to prevent an excess of air circulation, the closure element can be arranged and secured 15 over the outer end of the duct. When the duct is closed in the manner as stated, any condensation or liquid flowing down through the duct is free to escape through drainage passages 17 in the lower extremity 20 of the duct and in the front surface of the sill.

It will be noted that all of the exposed surfaces of the floor, gutter, molding strip and duct are protected by metal and protect 25 the wooden parts from water and moisture to prevent decay. In operation a clear, free and large passage is provided by the duct to promote a live and efficient circulation of air up over the inner surface of the glass plate to prevent moisture and frost collecting and water from condensation and washing 30 is readily drained outside from the gutter. The construction is inexpensive, simple

and easily applied for use and the glass plate readily secured permanently in place.

In accordance with the patent statutes I 35 have described the principles of operation of my invention, together with the apparatus which I now consider to represent the best embodiment thereof, but I desire to have it understood that the construction 40 shown is only illustrative, and that the invention can be carried out by other means and applied to uses other than those above set forth within the scope of the following 45 claim.

Having described my invention, what I claim as new and desire to protect by Letters Patent is:—

In a construction of the character set forth, the combination of a window casing 50 floor, a gutter above said floor, a glass plate resting edgewise above said floor and against said gutter, means for securing said plate in said position, a duct leading down from said gutter and terminating forwardly below said floor, for the purposes set forth, and a cover detachably secured 55 over the lower outer end of said duct, the wall of said duct being formed with a vent around said cover to the outer atmosphere. 60

In testimony whereof, I have signed my name to this specification.

HARRY E. JAMES.
